B. G. HARLEY

BOAT PROPELLER

Filed March 31, 1923

Fig. 3.

Fig. 4.

UNITED STATES PATENT OFFICE.

BERTRON G. HARLEY, OF NORTH TONAWANDA, NEW YORK.

BOAT PROPELLER.

Application filed March 31, 1923. Serial No. 629,083.

To all whom it may concern:

Be it known that I, BERTRON G. HARLEY, a citizen of the United States of America, and resident of North Tonawanda, in the 5 State of New York, in the United States of America, have invented certain new and useful Improvements in a Boat Propeller, described in the following specification and illustrated in the accompanying drawings, 10 that form part of the same.

The principal objects of the invention are to improve the construction of the support for the propeller shaft of boats of the "disappearing propeller" type so that the propeller shaft will be rigidly supported 15 against vibration in all positions, and to provide a simple and efficient operating gear.

The principal features of the invention consist in supporting a bearing for the propeller shaft upon a pivotal link carried by 20 a lever pivotally mounted in the propeller shaft housing.

In the drawings, Figure 1 is a longitudinal sectional view through the propeller shaft housing showing the propeller and its supporting members in elevation and in the raised position.

Figure 2 is a view similar to Figure 1 showing the propeller lowered.

30 Figure 3 is an enlarged cross sectional view through the structure taken on the line 3—3 of Figure 1.

Figure 4 is an enlarged cross sectional view taken on the line 4—4 of Figure 1.

35 The "disappearing propeller" type of boat in which the propeller shaft is provided with a universal joint and the flexible end of the shaft is raised and lowered from a housing in the bottom of the boat is well known but the means for supporting the shaft at the propeller end, in boats at present in use, do not effectively support the shaft against vibration.

In the construction herein shown, the 45 housing 1, open at the bottom, is of rectangular cross section at the forward end and between the side walls 2 is arranged a lever 3 supported on a pin 4 extending transversely of the casing. The ends of the pin 4 are journalled in trunnions 5 and 6 formed in the walls 2, the trunnion 5 being closed and the trunnion 6 is provided with a threaded cap 7 to allow the pin to be placed in position.

55 The lever 3 is preferably of an H section and extends longitudinally of the housing

which at suitable points in its length may be provided with parallel rubbing strips 8, though the trunnion support is of ample dimensions to be very rigid.

A shackle link 9 preferably of U shape in longitudinal section straddles the free end of the lever 3 and a pin 10 passing through the link and lever pivotally connects them together. The arms of the link 9 are preferably offset outwardly to straddle a bearing sleeve 11 in which the propeller shaft 12 is journalled. This sleeve is formed with a downwardly extending web 13 which is shaped to form a skeg extending below 70 and protecting the propeller 14. The web 13 is formed with bosses 15 and a pin 16 extending through the bosses 15 and the ends of the link 9 form a rigid pivot connection. The pin 16 is preferably rigidly secured in 75 the link arms by being swaged at the ends as also is the pin 10, thus obtaining the maximum pivot bearing surface.

It will be readily seen that a construction such as described will provide a very rigid 80 support for the propeller shaft in any position.

The lever 3 is rigidly secured to the pin 4 by the operating handle 17 which is threaded into the boss 18 on said lever and 85 enters a centered hole 19 in the pin.

The housing 1 is provided with a slot 20 through which the handle 17 projects and a slotted cap 21 is provided with an arc-shaped top concentric with the pin 4. The 90 outer surface of the cap is machined to a true surface and an arc-shaped plate 22 slidably arranged on the handle engages the outer face. A suitable grease cup 23 is arranged on the plate 22 to provide a grease 95 packing to prevent the leakage of water into the boat. Above the plate 22 is arranged a packing cap 24 which is shown held against the plate by a compression spring 25 surrounding the handle. The pressure of the 100 spring may be regulated by the nut 26 to hold the plate 22 tightly to its seat.

The preferred means for packing the handle, is here shown but other means may be devised to accomplish the desired result 105 of preventing leakage of water into the boat at this point.

In the operation of this device, the oscillation of the handle 17 swings the lever 3 down or up and the shackle link, swinging 110 freely depresses or raises the shaft bearing which remains always in the same position

on the shaft, that is, abutting the propeller hub, it being held in place by a suitable collar 27 on the shaft.

What I claim as my invention is:

- 5 1. In a boat propeller, the combination with a propeller shaft housing and propeller shaft, of a lever pivoted in said housing, a bearing for the propeller shaft held in fixed relation to the propeller, and a 10 double link straddling said bearing and pivotally connected thereto and to the end of said lever and slidably engaging said bearing.
- 15 2. In a boat propeller, the combination with a propeller shaft housing and propeller shaft, of a lever pivoted in said housing, a bearing for the propeller shaft held in fixed relation to the propeller and having a transverse journal below the shaft 20 journal, a double link pivoted on said lever embracing said shaft bearing, and a pivot pin secured in the links and extending through the transverse bearing of said journal.
- 25 3. In a boat propeller, the combination with a propeller shaft housing and propeller shaft, of a pin arranged transversely of said casing, trunnions in said casing supporting said pin, a cranked lever carried 30 on said pin having one end projecting from the housing, a link pivoted on the free end of the lever within the housing, and a propeller shaft bearing pivoted on said link.
- 35 4. In a boat propeller, the combination with a propeller shaft housing having a slot in the top, and a propeller shaft, of a lever pivoted in the housing, a bearing for the propeller shaft carried by said lever, a handle secured to said lever and projecting 40 through the slot in the housing, and slide- able means arranged on said handle for closing the slot in the casing.
- 45 5. In a boat propeller, the combination with a propeller shaft housing having a slot in the top, and a propeller shaft, of a lever pivoted in the housing, a bearing for the propeller shaft carried by said lever, and a handle secured to said lever and projecting through the slot in the housing.
- 50 6. In a boat, a housing for the propeller having a narrow portion to house the propeller shaft and an enlarged portion to house the propeller, the narrow portion having parallel rubbing strips extending from the top downwardly, a lever pivotally mounted in the forward end of the narrow

housing and slidably engaging said rubbing strips, a propeller shaft, a bearing mounted on the propeller end of the shaft, links connecting the free end of said lever with 60 said bearing, and a handle rigid with said lever extending upwardly through said housing.

7. In a boat propeller, the combination with a propeller shaft housing and propeller shaft, of a lever pivoted in said housing, a bearing for the propeller shaft held in fixed relation to the propeller and having a rigid skeg formed integral therewith and extending downwardly and rearwardly 70 therefrom, and a link connection between said lever and said bearing.

8. In a boat propeller, the combination with a propeller shaft housing having a slot in the top, and a propeller shaft, of a lever pivoted in the housing, a bearing for the propeller shaft carried by said lever, a handle secured to said lever and projecting through the slot in the housing, a slotted 75 arc-shaped cap secured to the casing, an arc-shaped plate encircling said handle and sliding on said cap, and spring means for holding said plate in contact with said cap.

9. In a boat propeller, the combination with a propeller shaft housing having a slot in the top, and a propeller shaft, of a lever pivoted in the housing, a bearing for the propeller shaft carried by said lever, a handle secured to said lever and projecting 85 through the slot in the housing, a slotted 90 arc-shaped cap secured to the casing, an arc-shaped plate encircling said handle and sliding on said cap, spring means for holding said plate in contact with said cap, and means for grease packing the contact faces 95 of said cap and plate.

10. In a boat propeller, the combination with a propeller shaft housing having a slot in the top, and a propeller shaft, of a lever pivoted in the housing, a bearing for the propeller shaft carried by said lever, a handle secured to said lever and projecting through the slot in the housing, a slotted 100 arc-shaped cap secured to the casing, an arc-shaped plate encircling said handle and 105 sliding on said cap, a packing cap engaging said plate slidably arranged on said handle, a spring encircling the handle above said packing cap, and a nut threaded on the handle above said spring.

BERTRON G. HARLEY.
